CHRISTMAS TREE ORNAMENT

Earl W. Carlson and Gwendolyn E. Carlson, both of
312 Riverdale Drive, Glendale, Calif.

Filed July 17, 1961, Ser. No. 65,943

Term of patent 7 years

(Cl. D29—1)

FIG. 3.

FIG. 1.

FIG. 2.

FIG. 4.

FIG. 5.

FIG. 1 is a side elevational view of a Christmas tree ornament showing our new design,

FIG. 2 is an edge elevational view,

FIGS. 3 and 4, are, respectively, top and bottom plan views, and

FIG. 5 is an enlarged, transverse, sectional view taken on the line 5—5 of FIG. 1.

The dominant features of our design for a Christmas tree ornament reside in a five pointed star having one of its points, which is in line with the mounting element for the ornament, radially longer than its other points, together with a crescent shaped band carried by the star with the points of the star projecting beyond the outer periphery of the crescent shaped band, all as shown.

We claim:

The ornamental design for a Christmas tree ornament, substantially as shown and described.
